UNITED STATES PATENT OFFICE

91,834

DESIGN FOR A GAME BOARD

Jacob E. Markle, Nashville, Tenn.

Application December 12, 1933, Serial No. 50,049

Term of patent 14 years

To all whom it may concern:

Be it known that I, JACOB E. MARKLE, a citizen of the United States, residing at Nashville, in the county of Davidson and State of Tennessee, have invented a new, original, and ornamental Design for a Game Board, for fourteen years of which the following is a specification, reference being had to the accompanying drawing, forming part thereof.

In said drawing, Fig. 1 is a plan view of a game board, showing my new design, Fig. 2 is a sectional view through center of bowl looking toward the front, Fig. 3 is an enlarged fragmentary view of the central portion.

It is to be noted that the elongated and num-

bered rectangles next the bowl and shown plainly in the detail Fig. 3 are merely indicated by numbers in Figure 1 because the small scale of this figure prevents the details being exactly shown as they actually appear in the device embodying the design.

It will also be noted that the numerals in the inner row each represents the sum of the numerals in the two squares on the same radius multiplied by one hundred.

I claim:

The ornamental design for a game board, as shown and described.

JACOB E. MARKLE.
